ELECTRIC TEMPERATURE CONTROL

Filed Aug. 27. 1925

2 Sheets-Sheet 1

The drawing shows a cross-sectional view of a mechanical assembly. At the top, a large rectangular block with diagonal hatching contains a central vertical channel. A horizontal tube 9 passes through this channel. A vertical pipe 14 is connected to the side of the block. Below the block, a horizontal pipe 5 is connected to a vertical pipe 12, which then connects to the horizontal pipe 9. A small valve 16 is located on the vertical pipe 12. A horizontal pipe 17 is connected to the side of the block, and a valve 15 is located on this pipe. A vertical pipe 18 is connected to the side of the block, and a valve 19 is located on this pipe. A vertical pipe 20 is connected to the side of the block, and a valve 21 is located on this pipe. A vertical pipe 22 is connected to the side of the block, and a valve 23 is located on this pipe. A vertical pipe 24 is connected to the side of the block, and a valve 25 is located on this pipe. A vertical pipe 26 is connected to the side of the block, and a valve 27 is located on this pipe. A vertical pipe 28 is connected to the side of the block, and a valve 29 is located on this pipe. A vertical pipe 30 is connected to the side of the block, and a valve 31 is located on this pipe. A vertical pipe 32 is connected to the side of the block, and a valve 33 is located on this pipe. A vertical pipe 34 is connected to the side of the block, and a valve 35 is located on this pipe. A vertical pipe 36 is connected to the side of the block, and a valve 37 is located on this pipe. A vertical pipe 38 is connected to the side of the block, and a valve 39 is located on this pipe. A vertical pipe 40 is connected to the side of the block, and a valve 41 is located on this pipe. A vertical pipe 42 is connected to the side of the block, and a valve 43 is located on this pipe. A vertical pipe 44 is connected to the side of the block, and a valve 45 is located on this pipe. A vertical pipe 46 is connected to the side of the block, and a valve 47 is located on this pipe. A vertical pipe 48 is connected to the side of the block, and a valve 49 is located on this pipe. A vertical pipe 50 is connected to the side of the block, and a valve 51 is located on this pipe.

ELECTRIC TEMPERATURE CONTROL.

Application filed August 27, 1925. Serial No. 52,948.

My invention relates to control systems, and it has particular relation to an electrical temperature control system.

One object of my invention is to provide a simple, reliable and accurate system of apparatus for use in controlling, either manually or automatically, the temperature of metal rolls, such as are used in calendering, ironing, rubber working and other machines including rolls which are heated or cooled under operating conditions.

Another object of my invention is to provide novel means for indicating the temperature at the surface of a roll under conditions of use, and the invention further contemplates a relatively simple device whereby the supply of a heating medium such as water, steam or electric current shall be automatically regulated in accordance with temperature changes at the working surface of the roll.

A further object of my invention is to provide a novel galvanometer control switch particularly designed to govern one or more electric circuits when the needle or other moving element of the galvanometer occupies a predetermined and definite position.

A still further object of my invention is to provide quick and accurate means for conveniently adjusting the deflection at which the galvanometer causes the operation of the switch.

A still further object of my invention is to provide means for varying the sensitivity of the galvanometer, whereby the current flow necessary to actuate the galvanometer needle to a selected position may be controlled without changing the zero setting of the instrument, or the position of the switch, thus effecting the adjustment of the selected position from a point outside the instrument, thereby avoiding the possibility of damage to the sensitive mechanism of the instrument.

With these and other objects and applications in mind, my invention further consists in the details of construction and operation and circuit arrangement, hereinafter described, and claimed and illustrated in the accompanying drawings, wherein

Fig. 1 is a diagrammatic view, partially in section, of circuits and apparatus embodying my invention;

Fig. 2 is an enlarged detail view, illustrating the electric connections between the motor-actuated switch, the galvanometer and the water heater; and

Fig. 3 is a detail view of a modification.

In the illustrated embodiment of my invention shown in the drawing, a hollow roll 1 is mounted in bearings 2 and 3 and it is driven from a suitable source of power (not shown) through a gear or pulley 4. In the case illustrated, the roll is designed to be heated by water supplied through a pipe 5 from an electric water heater 6 and extending into one end of the roll through a suitable stuffing box or equivalent device (not shown). The water flows out of the roll through a waste pipe 7.

In accordance with my invention, at a suitable point in the cylindrical or working surface of the roll preferably adjacent its central plane, I form an inwardly tapering hole in which I mount a steel or other suitable metallic plug 8. This is centrally perforated for the reception of a conductor 9 one end of which is welded at 8a to said plug at the outer surface thereof so as to be flush with the cylindrical surface of the roll in which it is mounted. The roll itself is of steel or cast iron and constitutes one of the elements of a thermocouple, while the conductor 9, which is made of constantan or some other nickel alloy, constitutes the second element of the couple.

Within the plug 8, the conductor 9 is suitably insulated to within a short distance of its welded extremity by a porcelain or other refractory tube 10 and from this tube within the roll 1 it is provided with a suitable flexible insulating covering 11, being extended through one neck of the roll to a suitable terminal 12 on the outside of one end of the latter. Adjacent this end of the roll, I mount on it an insulating structure 13 carrying a metallic contact ring 14 and on the bearing 3, I mount an arm 15 carrying a brush 16 electrically engaging said latter ring. From this brush and from the bearing 3 or other suitable portion of the frame in which the roll 1 is mounted, I run a pair of compensating leads 17 and 18 to a box or container 19 kept by any suitable means at a constant temperature. For example, said

box may be supplied through a pipe 20 with steam at atmospheric pressure so that the terminals of the wires or leads 17 and 18 within it are likewise maintained at all times 5 at the same temperature.

From the terminals of said leads within the box 19 I run two conductors 21 and 22 to a suitable indicating galvanometer 23 and may also extend branch conductors 24 and 10 25 to a recording galvanometer or equivalent device 26. These instruments 23 and 26 are properly calibrated in degrees so that they respectively indicate and record the temperature at the hot junction of the thermocouple 15 comprised by the roll 1 and conductor 9. Moreover it is noted that temperatures shown are those of the external or working surface of said roll 1, so that by the means described it is possible to obtain accurate 20 readings or indications of that portion of the roll engaging whatever material is operated on.

If it is desired to automatically regulate the supply of heating medium to the roll, I 25 may provide such an arrangement of apparatus as that shown in the drawings and more especially as illustrated in Fig. 2. For the purpose noted, the coil or heating element 30 of the electric heater 6 is connected 30 to a suitable form of motor-actuated switch 31 which includes an oscillatory or pivotally mounted blade 32 capable of simultaneously engaging either of two pairs of fixed contacts 33-34 or 35-36. This blade is de- 35 signed to be actuated by an electric motor 37 through suitable quick break mechanism which after said motor has been started, causes the blade to instantaneously move from engagement with one pair of contacts 40 into engagement with the other pair whereon it remains until the motor is again operated. The contacts 36 and 33 of the switch are both connected to a current supply line 38 and a second current supply main 45 is 45 connected to one terminal of the heating element 30 as well as to a terminal 39 connected to one of the terminals of the motor 37. The second terminal of said motor is connected to a terminal 40.

50 In addition to the motor-controlled switch 31, I provide a controlling galvanometer 41 for governing a pair of switches having three terminals 42, 43, and 44 of which the first is connected to the terminal 35 of the switch 31. The terminal 43 is connected to the terminal 40 and the terminal 44 is connected to the motor terminal 34. The second current supply lead 45 is connected to the motor terminal 39 and to one terminal of the heating 55 coil 30.

The galvanometer 41 may be of any suitable construction capable of being actuated by the current produced by the thermocouple comprised by the elements 1 and 9 and 60 65 includes a movable element in the form of

a swinging or pivotally mounted needle 46. The winding 41^a of the galvanometer is connected in circuit with two terminals 47 and 48 to which are connected the leads 21 and 22 and in one of these leads I preferably connect a control rheostat 49 whereby the current flow from the thermocouple may be adjusted to produce any desired deflection of the needle 46.

The rheostat of the control rheostat 49 is 75 one of the important features of my invention, inasmuch as the range of the galvanometer may be quickly and easily adjusted without the necessity for shifting the switches to the zero position of the galvanometer needle, as required by the prior art. In accordance with the present construction, said contacts and said zero position remain unchanged, and it is only necessary to vary the control rheostat 49 when the selected position 80 for the galvanometer needle is to be varied. A further advantage of the present method is that the sensitivity of the galvanometer 41 is increased as the desired maximum temperature reading is decreased, whereas in the 85 prior art constructions, the sensitivity remains unchanged as the zero position of the instrument is depressed or the contacts adjusted.

90 Mounted to cooperate with the needle 46 is 95 a depressor 50 in the shape of a substantially horizontal element mounted over said needle adjacent the free end thereof and having at its extremity downwardly projecting stops 51-51 which limit the possible swing of said 100 needle. This depressor, by suitable mechanism (not shown) but well known to the art, is designed to periodically engage and move downwardly the needle 46. Under the needle and in such position as to be engaged 105 thereby when it is depressed, I mount two levers 52 and 53 in the form of two aligned bars so mounted as to extend in substantially the same horizontal line, with their short arms immediately adjacent each other but 110 spaced apart. At the end of the long arm of the lever 52 is mounted an insulated contact 54 and a similar contact 55 is mounted on the end of the long arm of the lever 53 while adjacent and immediately above these 115 two contacts are mounted two fixed contacts 56 and 57, the arrangement being such that if, when the depressor 50 is lowered, the needle 46 lies over the short arm of one of the levers, that lever will be turned on its fulcrum and the contact on its long arm will be moved into electrical engagement with the corresponding fixed contact. The space between the adjacent ends of the levers 52 and 53 is of such width that if the needle 46 is 120 immediately over it when the depressor is lowered, neither lever will be actuated, this position of the needle being that corresponding to the selected temperature at which it is 125 desired the surface of the roll shall be main- 130

tained. The two fixed contacts 56 and 57 are respectively connected to the terminals 42 and 44, while the two movable contacts 54 and 55 are both connected to the middle terminal 43.

With the above described arrangement of parts, if current from a suitable source is supplied to the conductors 38 and 45, with the motor switch blade 32 in the position illustrated, and if cold water be supplied to the electric heater 6 and delivered therefrom through the pipe 5 to the roll 1, current will flow from the line 38 through the blade 32 to the heating coil 30 and thence to the line 45 so that said water will be heated. The temperature of the surface of the roll is thus gradually raised and if the actuating mechanism of the depressor 50 be set in operation, said depressor will periodically move down and as long as the needle 46 of the galvanometer lies over the short arm of the lever 52, the contact 54 of this lever will be moved into engagement with the fixed contact 56 at each operation of said depressor. This, however, causes no operation of any of the apparatus since this particular pair of contacts is open circuited.

As the temperature of the roll 1 approaches the predetermined desired point, the galvanometer needle 46 moves toward the right, and when said temperature reaches said point, said needle, by proper adjustment of the rheostat 49 is caused to occupy a position immediately over the space α between the adjacent ends of the levers 52 and 53. Should it be desirable at any time to vary the selected position for the galvanometer or needle 46, it is only necessary to adjust the control rheostat 49.

When the depressor 50 acts, neither of the levers 52 or 53 is moved. Inasmuch, however, as current is still supplied to the coil 30, the temperature of the water in the heater 6 continues to rise, so that the roll temperature is also increased. The current produced by the thermocouple formed by the roll 1 and element 9 is consequently increased in amount, so that the galvanometer needle 46 swings further toward the right, with the result that subsequent action of the depressor 50 causes the lever 53 to be turned on its fulcrum, thus bringing its contact 55 into engagement with the contact 57. Current is now free to flow from line 38 through the switch blade 32 to the contact terminal 44 thence through the contacts 57 and 55 to the contact terminal 43, to the contact 40 through motor 37 to contact terminal 39 and to the line 45. Said motor is thereupon put into operation and moves the switch blade 32 from the position shown in the drawings into engagement with the contacts 35 and 36. This cuts off current from the coil 30 of the heater 6, so that there is no further rise in temperature of the water delivered to the roll 1

which is now cooled by said water. The switch blade 32 is, however, thus set so that while no action occurs as long as the galvanometer needle 46 is moved by the depressor into engagement with the lever 53, or is moved into the space between the levers, as soon as the temperature of the roll has fallen to such a point that said needle swings over the short end of the lever 52, the next subsequent action of the depressor will cause the contact 54 to be moved into engagement with the contact 56. Thereupon current will flow from the line 38 through the blade 32, to contact terminal 42, thence through contacts 56 and 54 to contact terminal 43 thence to contact terminal 40 through motor 37 to contact terminal 39 and to line 45 starting motor 37 and causing it to move switch blade 32 into the position shown in the drawings in engagement with the contacts 33 and 34. Current is now free to flow from the line 38 through the blade 32 to the heating coil 30 and the line 45, and while no further action of the motor 37 occurs by reason of the action of the depressor 50 as long as the needle 46 lies over the lever 52 or over the space between the levers, an increase in the temperature of the roll with a corresponding increase of the thermoelectric current delivered to the galvanometer 41 will cause the needle to again move over the lever 53, whereupon the above described cycle of operations is repeated.

At any time the temperature of the working surface of the roll may be noted from the indicating galvanometer 23 and a record of the temperature variations of said working surface continuously made by the instrument 26.

The supply of heating medium to the roll 105 is automatically governed by the apparatus described, so that the roll temperature is maintained between relatively narrow limits which may be accurately adjusted by the rheostat 49. If the amount of resistance in 110 the galvanometer circuit is increased, a higher temperature of the roll will be required to generate sufficient current to deflect the needle 46 into such a position that it may be depressed into engagement with 115 the lever 53 which controls the cutting off of the current to the heater 6.

As shown in Fig. 3, I may in place of the electric heater 6 employ an electric magnet 60 to operate a valve 61 which in one position permits steam to flow from a pipe 62 to the roll 1 and in another position into which it moves under the action of gravity cuts off the supply of steam and permits cold water from a pipe 63 to be delivered to the roll. 120 This electromagnet 60 will be connected with the apparatus shown in Fig. 3 in place of the coil 30 so that when it is energized, it will open the valve to allow steam to flow to the roll and when it is deenergized it will 125 130

fall under the action of gravity to cut off the steam and permit the flow of cold water. If desired, the cold water connection to the above valve may be omitted without departing from my invention where positive cooling of the roll is not required.

While I have shown several embodiments of my invention, for the purpose of describing the same and illustrating its principles of construction and operation, it is apparent that various changes and modifications may be made therein without departing from the spirit of my invention and I desire, therefore, that only such limitations shall be imposed thereon as are indicated in the appended claims or as are demanded by the prior art.

I claim:—

1. The combination with a roll adapted to constitute one element of a thermocouple, of means controlled by said thermocouple for regulating the temperature of said roll, said means including means for varying the temperature at which said roll is to be maintained.
2. The combination of a heated metallic roll, an element electrically connected with the roll to constitute therewith a thermocouple, and means controlled by the current from said thermocouple for regulating the temperature of the roll.
3. The combination of a heated metallic roll, an element electrically connected with the roll to constitute therewith a thermoelectric couple, an electrical instrument actuated by current generated by said thermocouple, and mechanism controlled by said instrument for governing the supply of heating medium to the roll.
4. The combination of a metallic roll, an element electrically connected with the roll to constitute therewith a thermoelectric couple; an electrical instrument actuated by current generated by said thermocouple, and

mechanism controlled by said instrument for governing the temperature of the roll.

5. The combination of a metallic roll, an element electrically connected with said roll to constitute therewith a thermocouple, an electrical instrument actuated by current from said thermocouple, and means governed by said instrument for maintaining the temperature of said roll substantially constant.

6. The combination of a metallic roll, an element electrically connected with said roll to form therewith a thermocouple, an electrical instrument actuated by current from said thermocouple, and means governed by said instrument for maintaining the temperature of said roll at a predetermined point, with means for adjusting said electrical instrument to vary the temperature at which said roll is maintained.

7. The combination with a metallic roll constituting one element of a thermocouple, an electrical instrument including a movable element actuated by current from said thermocouple, a periodically actuated depressor operative on the movable element, and an electric switch positioned to be actuated by the movable element when the latter occupies a predetermined position when depressed.

8. The combination with a roll adapted to constitute one element of a thermocouple, of an electrical instrument connected to said roll and including a movable element, a depressor periodically acting on said movable element, an electric switch positioned to be actuated by the movable element when the latter occupies a predetermined position when depressed, and means for adjusting the calibration of said electrical instrument.

In testimony whereof, I have hereunto subscribed my name this 24th day of August, 1925.

CHARLES B. THWING.
